UNITED STATES PATENT OFFICE.

DWIGHT C. SUMNER, OF NEW YORK, N. Y.

DESIGN FOR ORNAMENTING CLOTH.

SPECIFICATION forming part of Design No. 12,709, dated January 24, 1882.

Application filed December 27, 1881. Term of patent 3½ years.

To all whom it may concern:

Be it known that I, DWIGHT C. SUMNER, of New York, in the county and State of New York, have invented a new and original Design for Ornamenting Cloth, of which the following is a specification.

The accompanying drawing represents a face view of my new design.

This design relates to a new ornamentation for cloth by means of depressed grooves or furrows. The cloth is ornamented by series of undulating lines or grooves and intervening diagonal lines or grooves, every said series being separated by a dotted space, as hereinafter more clearly specified.

In the drawing, A represents a piece of cloth

ornamented according to my new design. B B are parallel stripes, each consisting of outer undulating grooves or furrows, a, and intervening diagonal grooves or furrows, b. Between the stripes B B are spaces C, that are ornamented by dots d.

I claim—

The design for ornamenting cloth, consisting of the undulating grooves or furrows a, diagonal grooves or furrows b, and dots d, substantially as shown.

DWIGHT C. SUMNER.
